UNITED STATES PATENT OFFICE

JAMES MILNES, OF STRUTHERS, AND RAY E. HOWELL, OF POLAND, OHIO

ROLL HEATER

Application filed May 2, 1931. Serial No. 534,505.

The present invention relates to means for heating the rolls of a rolling mill preparatory to their being utilized for hot rolling sheets, plates, and the like.

For satisfactory rolling of certain classes of these articles it is requisite that the rolls of the mill be at a relatively high temperature which, after the rolls have once been raised thereto, is thereafter substantially maintained automatically through heat received by the rolls from the hot material passing between them.

One method heretofore widely practiced for preliminarily heating the initially relatively cold rolls is to successively pass through the mill a plurality of hot sheets so as to gradually raise the temperature of the rolls by absorption of heat therefrom. This practice is, however, unsatisfactory and uneconomical for, as the temperature of the rolls increases, their dimensions vary somewhat as the result of their expansion with consequent variation in the thickness of the rolled sheets, while until the rolls attain the proper rolling temperature the finish on the material passing therethrough is more or less imperfect. As a result, many of the sheets rolled during the heating operation do not meet the required commercial standard and must be classed as "seconds", while as the rolls are usually of relatively large mass the time required for heating them in this way to the desired temperature is excessive with the result that the entire mill and associated mechanisms are necessarily engaged for several hours in relatively unproductive or at least inefficient operation before a proper rolling condition is obtained.

With a view to obviating the disadvantages of the heating-up method to which reference has just been made, various forms of mechanical means have been suggested for heating the rolls either in the mill stand or in an apparatus separate therefrom but, so far as we are aware, all of them are open to the objection that the rolls must be rotated for the several hours required to heat them evenly and uniformly and thereby avoid the setting up of internal strains, cracking, burning and other inimical effects incident to uneven or

too rapid heating or impingement of a heating flame for too long a period on the roll surfaces. Consequently, a very large amount of power is unproductively expended in driving the rolls while they are being heated up, particularly, and as usually the case, when the rolls are of large size and weight, while a further disadvantage of this class of apparatus when designed to operate on the rolls while the latter are disposed in the mill stand resides in the fact that the mill is necessarily idle insofar as its primary function is concerned while the rolls are being heated, with resultant lowering of its possible productive capacity.

For the reason last mentioned, the use of apparatus adapted to heat the rolls prior to their being placed in the mill is generally preferred but since, as just explained, it has hitherto been necessary to rotate the rolls when disposed in the heater in order to heat them uniformly and evenly, the cost of bringing the rolls to the proper temperature because of the power required to drive them during the heating operation has been excessive. Consequently, as the power so used is totally unproductive, some operators prefer to dispense with a separate heater and to employ the heating up method to which we have initially referred, since in that way the power expended for driving the mill is at least to some extent usefully employed even though much of the rolled material produced before the rolls have attained the most desirable rolling temperature is not of first quality.

A principal object of the present invention, therefore, is to provide a roll heater of the type in which the rolls are heated apart from the mill stand, yet of such character that the heating may be satisfactorily accomplished with the expenditure of a minimum amount of power; which may be operated by unskilled labor and substantially without attention during the heating period, and which is effective to heat the rolls evenly and uniformly in a minimum of time.

A further object of the invention is the provision of a roll heater of the character of that to which reference has just been made

in which the rolls remain stationary throughout the heating period and the heating means are oscillated with respect to the rolls so as to properly distribute the heat thereto with resultant negation of localized heating and the inimical effects incident thereto.

A still further object of the invention is the provision of a roll heater adapted to heat the rolls when stationarily supported therein through the medium of a plurality of gas or other suitable burners disposed adjacent thereto and arranged for relative oscillation with respect to the rolls in combination with means for effecting such oscillation, whereby as the mass of the oscillatory burners and associated moving parts is relatively small compared to the mass of the rolls, the power required for the operation of the heater is correspondingly reduced over that required for the operation of roll heaters in which the rolls are rotated during the heating period.

A still further object of our invention is the provision of a roll heater of relatively simple yet rugged construction; which is not liable to get out of order or become damaged under the conditions of use to which it is necessarily subjected in the performance of its intended function, and in which the heat is effectively used with resultant economy in operation.

Other objects, advantages and novel features of construction and arrangement comprehended by the invention are hereinafter more specifically mentioned or will be apparent from the following description of a preferred embodiment thereof, reference being had to the accompanying drawings.

As will hereinafter more fully appear, that embodiment of the invention herein shown and described is intended for heating one pair of rolls at a time, the rolls during the heating operation being substantially enclosed within a suitable casing which forms the heating unit or chamber and in which suitable burners are arranged in proximity to each of the rolls for relative oscillation with respect thereto. However, if desired, a plurality of the heating units may be provided, each designed to contain a pair of rolls and the several burners respectively disposed therein oscillated from a single power source or, under certain conditions, each heating unit may be arranged to contain more than a pair of rolls and the burners therein similarly oscillated from a single power source, all as hereinafter more particularly pointed out.

In the accompanying drawings, Fig. 1 is a top plan view of the roll heater showing a pair of rolls disposed therein in position to be heated preparatory to being transferred to the mill stand, portions of the cover of the heating unit being broken away for clearness

of illustration; Fig. 2 is a longitudinal vertical staggered section substantially on the line 2—2 in Fig. 1 with certain parts shown fragmentarily in side elevation; Fig. 3 is a vertical transverse section generally on the line 3—3 in Fig. 2 but with certain parts shown in elevation and fragmentarily broken away to illustrate internal construction; Fig. 4 is a detail top plan view of one of the burners and associated parts removed from the heater, and Fig. 5 is a side elevation of the structure shown in Fig. 4, portions of the branches of the burner being broken away into vertical section. In the several figures like characters are used to designate the same parts.

Broadly considered, the roll heater illustrated comprises means for supporting a pair of rolls in horizontal parallel relation within a casing which is substantially closed during the heating operation and portions of which may desirably be heat insulated in order to effect conservation of fuel by reduction of radiation; within this casing gas burners or other heating means are disposed adjacent the rolls and arranged for oscillation with respect thereto, while suitable means are provided for effecting such oscillation in order to properly distribute the heat over the roll surfaces.

More particularly, the heating unit, generally designated 1, in which the rolls R, R' are disposed comprises a hollow, generally rectangular base 2, conveniently a single unitary casting, the sides of which are provided in their upper surfaces with longitudinally spaced transversely aligned semicylindrical recesses 3, 3 adapted to receive and form seats for, the necks of the rolls when the latter are lowered into place therein by a crane or other suitable means. These recesses are so arranged that the rolls when disposed therein will lie in longitudinally spaced relation as best shown in Figs. 1 and 2 with the central portions or barrels of the rolls which are to be heated between the sides of the base which latter is desirably provided with a transversely extending web 4 which serves to tie the sides of the base together midway of its ends. The upper horizontal surface of the base is flat to form a seat for a removable cover 5 which is desirably formed of sheet metal suitably braced and so shaped, as best shown in Fig. 2, as to lie fairly closely adjacent the rolls when the latter are disposed in the unit, the sides of the cover being provided with semicircular cut-outs to receive the upper half of the roll necks. The cover is preferably provided with a heat insulating lining 6 and with lifting eyes 7 to enable it to be conveniently removed from the base, while at its center a flue 8, which may be provided with a damper 9, is arranged to permit escape of the spent gases; this flue may exhaust directly into the air as

shown or may be connected with a chimney or the like so as to remove the spent gases from the vicinity of the apparatus.

It will thus be apparent that when the cover 5 is removed the rolls R, R' can readily be lowered into position in the base and that when the cover is thereafter replaced, the upper halves of the rolls will lie in a substantially closed chamber formed by the cover 10 and the lower halves in the chamber formed in the base.

Within the base beneath each roll and extending up on each side thereof considerably beyond its axis, is disposed a jacket 10 in 15 which the burners are secured, and since the arrangement of the jacket, burners and other parts is the same for each roll, we shall refer more particularly to those adjacent the roll R, the corresponding parts adjacent the other roll being designated by the same numbers with the addition of a prime ('). Each jacket, which may desirably be a unitary and relatively light casting although under certain conditions it may be made of sheet metal 20 suitably strengthened and reinforced, follows in transverse section the contour of a circle of somewhat greater diameter than the barrel of the adjacent roll but is cut away on its upper side sufficiently to permit the roll 25 to be lowered into and removed from the roll seats in the base; is arranged coaxially with the roll, and is supported for oscillation thereabout on semi-circular oppositely inwardly directed flanges 11 integral with the 30 sides of the base, bearing shoes 12 of hardened steel, bronze or the like being desirably interposed between the flanges and the adjacent ends of the jacket so as to minimize wear. The adjacent inner ends of the flanges desirably merge into the transversely extending web 4 and their outer ends into the adjacent upper marginal portion of the base.

Within each jacket is arranged a heating burner, the construction of which is best 45 shown in Figs. 4 and 5, from which it will be noted that each burner comprises a plurality of parallel circumferentially spaced pipes 14 adapted to extend axially of the roll and which are perforated on their inner 50 faces for the passage of the heating gas. These pipes, four of which are usually provided, are connected by a transversely extending header 15 suitably curved to conform to the jacket and which, at its center, 55 is in turn connected to a downwardly extending pipe 16 which passes through a hole in the jacket and terminates therebelow within the hollow base, at which point it is connected to a flexible tube 17 of metal or rubber 60 in turn connected at its lower end to a horizontally disposed pipe 18 extending to a swivel joint 19 communicating with the main supply pipe 20 as best shown in Fig. 3. Thus, when the jacket oscillates as herein- 65 after described, the horizontal pipe 18 can

swing about the swivel joint 19 while the flexible tube 17 can move upon itself as required so that the flow of gas to the burner pipes 14 is at all times maintained irrespective of the movements of the jacket. For convenience of illustration, the pipe 18 and adjacent parts are omitted from Fig. 2.

The burner pipes 14, header 15 and pipe 16 may desirably be welded together so as to form a single unitary structure, which after disposition in the jacket is rigidly connected to the inner surface thereof by straps 22 extending over the pipes 14 at suitable intervals or in any other convenient way.

It will thus be apparent that each jacket with its contained burner is capable of axial oscillation with respect to the roll about which it is disposed and suitable means are provided for effecting this oscillation of both jackets simultaneously during the heating operation. To this end each jacket may be provided at a point equidistant from its upper extremities with a downwardly depending crank arm 25 which may be integral with the jacket or suitably secured thereto in any convenient way and may either comprise a single member or, as shown, a pair of spaced members adapted to receive between them a longitudinally extending connecting rod 26

pivotaly attached to the arm by a pivot pin 27. The connecting rod extends through an opening 28 in the end wall of the base and for a convenient distance therebeyond, at

which point it is pivotally connected to the lower end of a rocker arm 29 extending generally vertically and mounted on a horizontally extending shaft 30 carried in suitable pedestals 31, the rocker arm comprising either a single element or preferably, and as shown, a pair of similar elements disposed on opposite sides of the connecting rod. The arm is extended above the shaft 30 and there pivotally connected to a pitman 32 extending to

a crank 33 on a shaft 34 in turn connected through a suitable reduction gear housed in a casing 35 with a motor 36 or other suitable source of power adapted to rotate the shaft 34. It will, of course, be understood that the form and construction of the reduction gear

is a matter of choice, so long as it is effective to bring about a suitable reduction in speed between the motor shaft and the shaft 34 and, incidentally, corresponding increase in power. As shown, the motor and reduction gear may conveniently be mounted on a

suitable base adjacent the pedestal 31, which, under ordinary conditions, will be located quite closely adjacent the base 2 so as to reduce the length of the connecting rod 26.

As the arms 25, 25' are both connected to the rod 26, the generally reciprocating movement of the latter communicated thereto by the rocker arm 29 is effective to oscillate the jackets 10, 10' and burners carried thereby

about the rolls R, R' simultaneously, the va-

rious parts through which the oscillation of the jackets is brought about being preferably so arranged that the amplitude of movement is sufficient to move each of the burner pipes 14 through overlapping or substantially overlapping arcs so as to effect an even distribution of the heat from the several burner pipes over the surface of the adjacent roll. In the particular embodiment of the invention shown, the parts are so arranged that the jackets are oscillated through an arc of approximately 90° with the result that the paths of the uppermost burner pipes 14 will not intersect or overlap at the top of the rolls and a small area of the roll surface at this point will thus never be directly exposed to the flames from the burners. Under practical conditions of operation this is ordinarily immaterial since the temperature in the upper part of the heating unit is usually considerably greater than at lower levels therein, but it will readily be apparent that by giving the jackets a slightly greater amplitude of oscillation through a suitable arrangement of the driving means the paths of the burners 14 adjacent the top of the roll can be caused to overlap and the entire surface of the roll thereby exposed to the direct action of the heating flames.

It will be noted that the diameter of the jackets is sufficient to afford an ample clearance between the burner pipes and the surface of the rolls and that the jackets are desirably provided with inwardly directed end flanges 40 whose inner edges lie more closely adjacent the roll surfaces to assist in preventing the escape of heat endwise therefrom, while the openings in the jackets through which the rolls are introduced and removed are desirably made as narrow as may be without interfering with the passage of the rolls.

While the apparatus shown in the drawings comprises but a single heating unit adapted to receive a pair of rolls, a plurality of such units if desired may readily be disposed in longitudinal alignment and the respective jackets and burners thereof oscillated from the same source of power by merely continuing the connecting rod 26 through the several units as indicated in broken lines in Figs. 1 and 2, or each unit may be arranged to receive more than a single pair of rolls, thus in either case enabling a plurality of pairs of rolls to be heated at the same time.

Since the combined mass of the moving parts including the jackets and burners is relatively light in comparison to the mass of the rolls with which they are operatively associated, the power required for oscillating them is relatively small in comparison to that which would be required for driving the rolls so that, through the medium of our invention, the advantages incident to heating the rolls apart from the mill stand can be secured without entailing the large ex-

pense for unproductive power incident to the use of separate heaters in which the rolls must be rotated in order to properly heat them. Moreover, since the heating flames are constantly being moved over the surface of the rolls while the heating is in progress, the chance of localized heating is obviated, while as the heat is efficiently applied and retained in proximity to the rolls the heating of the latter is uniformly, evenly and rapidly effected with a minimum expenditure of fuel.

While we have described one embodiment of our invention with considerable particularity, we do not thereby desire or intend to specifically confine or limit ourselves thereto or to any precise details in the design and construction of the various parts, as numerous changes and modifications may be made both in the general arrangement of the principal elements and in constructional details thereof without departing from the spirit and scope of the invention as defined in the appended claims.

Having thus described our invention, we claim and desire to protect by Letters Patent of the United States:

1. A roll heater comprising means adapted to support the roll to be heated, heating means, means for supporting said heating means adjacent the roll when disposed in heating position, and means for causing rotative motion of said heating means relative to the roll surface.

2. A roll heater comprising means adapted to support a roll to be heated, heating means, means for supporting said heating means adjacent the surface of the roll when disposed in heating position, and means operable to move the heating means relatively to the roll in a path substantially concentric therewith.

3. A roll heater comprising means adapted to stationarily support the roll to be heated, a heating burner adapted to partially surround and to direct a plurality of flames toward the surface of the roll when disposed in heating position, means for supporting the burner for limited oscillation circumferentially of the roll, and means for oscillating said supporting means.

4. A roll heater comprising a base arranged to support the roll to be heated, a removable cover for the base adapted to substantially enclose the roll when disposed in heating position, a burner having a plurality of annularly spaced branches, means for supporting the burner coaxially with the roll, and means for oscillating said supporting means and the burner relatively to the roll.

5. A roll heater comprising a base provided with seats for supporting the necks of the rolls to be heated, a removable cover extending over the base and adapted to substantially enclose the roll when in position to be heated, a jacket movably supported on the base and

operative to partially surround the roll, a burner disposed in the interior of the jacket operative to direct heating flames toward the roll, and means for oscillating the burner 5 and the jacket as a unit relatively to the roll.

6. A roll heater comprising a hollow base provided with seats for receiving the necks of the roll to be heated and inwardly directed, substantially semi-circular flanges arranged coaxially with said seats, a jacket supported on said flanges and adapted to partially surround the roll, a burner disposed in the interior of the jacket and having a plurality of branches extending parallel to the 10 axis thereof, means for conducting a heating medium to the burner, and means for oscillating the jacket on said flanges.

7. A roll heater comprising a hollow base provided with seats for receiving the necks 20 of the roll to be heated and inwardly directed, substantially semi-circular flanges arranged coaxially with said seats, a jacket supported on said flanges and adapted to partially surround the roll, said jacket having an opening in its upper portion through which the roll can be introduced, a burner disposed in the interior of the jacket and having a plurality of branches extending parallel to the axis thereof, means extending 25 through the wall of the jacket for conducting a heating medium to the burner, and means for oscillating the jacket on said flanges.

8. A roll heater comprising a hollow, substantially rectangular base provided with seats adapted to receive the necks of the roll to be heated and with inwardly oppositely directed, substantially semi-circular flanges 35 respectively disposed adjacent and coaxially with said seats, a removable cover for the base, a jacket supported on said flanges and having an opening through which the roll to be heated may be disposed inside the jacket and on said seats, a burner having a plurality of branches extending parallel with 40 the axis of the jacket and secured in the interior thereof, means for supplying a heating medium to the burner, and means including a connecting rod extending to a point remote from the base, a rock shaft, and means for actuating the rock shaft operable to oscillate the jacket about its axis to thereby cause the burner to reciprocate circumferentially about the roll through a limited arc.

55 9. A roll heater comprising a base having seats adapted to receive the necks of the roll which is to be heated, a jacket adapted to partially surround the roll when disposed on said seats, means for supporting the jacket 60 for axial oscillation, a burner within the jacket and movable therewith, said burner comprising a plurality of annularly spaced branches, and means for oscillating the jacket about its axis with an amplitude

sufficient to cause the paths traveled by adjacent branches of the burner to overlap.

10. A roll heater comprising a base having 70 seats adapted to receive the necks of the roll which is to be heated, a jacket adapted to partially surround the roll when disposed on the seats and extending within the base, means carried by the base for supporting the jacket for axial oscillation, a burner within the jacket and movable therewith, said burner comprising a plurality of annularly spaced branches extending parallel to the axis of the jacket, and means for oscillating the jacket about its axis with an amplitude 75 sufficient to cause the paths traveled by adjacent branches of the burner to overlap.

11. A roll heater comprising means for stationarily supporting a pair of rolls with their axes in parallel spaced relation, a jacket 80 adapted to partially surround each roll when so supported, means operative to support the jackets for oscillation about their respective axes, a burner disposed in each jacket, means for supplying a heating medium to the burners, and means for oscillating both jackets simultaneously about their respective axes.

12. A roll heater comprising means for stationarily supporting a pair of rolls with their axes in parallel spaced relation, a jacket 85 adapted to partially surround each roll when so supported, means operative to support the jackets for oscillation about their respective axes, a burner disposed in each jacket and comprising a plurality of circumferentially spaced branches extending parallel to the axis of the jacket, means for supplying the heating medium to the burners, and means for oscillating both jackets simultaneously about their respective axes through an arc sufficient 90 to cause the paths traveled by adjacent branches of the burners to overlap.

13. A roll heater comprising means adapted to support a roll to be heated, heating means, means for supporting said heating means adjacent the roll when disposed in heating position, and means operable to oscillate the heating means relatively to the roll.

14. A roll heater comprising means adapted to support a roll to be heated, heating means, means for supporting said heating means adjacent the roll when disposed in heating position, and means operable to oscillate the heating means about the axis of the roll.

In witness whereof, we have hereunto set our hands this 29th day of April, 1931.

JAMES MILNES.
RAY E. HOWELL.
